US0D1062560S

(12) **United States Design Patent** (10) **Patent No.:** **US D1,062,560 S**
(45) **Date of Patent:** **** Feb. 18, 2025**

(54) **POWER CONTROL UNIT**

(71) Applicant: **GUANGDONG EPROPULSION TECHNOLOGY LIMITED,**
Dongguan (CN)

(72) Inventors: **Youquan Yuan**, Guangdong (CN);
Yuefeng Liu, Guangdong (CN); **Weifu Yuan**, Guangdong (CN)

(**) Term: **15 Years**

(21) Appl. No.: **35/519,970**

(22) Filed: **Feb. 8, 2023**

(80) **Hague Agreement Data**

Int. Filing Date: **Feb. 8, 2023**

Int. Reg. No.: **DM/231089**

Int. Reg. Date: **Feb. 8, 2023**

Int. Reg. Pub. Date: **Feb. 9, 2024**

(30) **Foreign Application Priority Data**

Sep. 8, 2022 (CN) 202230595946.2

(51) **LOC (15) Cl.** **12-16**

(52) **U.S. Cl.**

USPC **D12/179**
